United States Patent

Des. 236,075
Patented July 29, 1975

236,075

UTILITY PAIL OR THE LIKE

Henry Golden, 1571 Elmwood Ave. 14620, and Samuel R. Genca, 36 Longcroft Road 14609, both of Rochester, N.Y.

Filed Jan. 9, 1974, Ser. No. 432,085

Term of patent 14 years

Int. Cl. D7—07

U.S. Cl. D7—187

FIG. 1.

FIG. 2.

FIG. 3.

FIG. 4.

FIG. 5.

FIG. 1 is a perspective view of a utility pail showing our new design:

FIG. 2 is a side elevational view, both sides being the same;

FIG. 3 is an end elevational view, both ends being the same;

FIG. 4 is a top plan view; and

FIG. 5 is a bottom plan view.

We claim:

The ornamental design for a utility pail or the like, as shown and described.
